(57) **CLAIM**

We claim the ornamental design for a faucet and soap
dispenser set, as shown and described.

DESCRIPTION

FIG. 1 is a front, right, perspective view of the faucet and
soap dispenser set;

FIG. 2 is a front side view of the claimed design;

FIG. 3 is a rear side view of the claimed design;

FIG. 4 is a right side view of the claimed design;

FIG. 5 is a left side view of the claimed design; and,

FIG. 6 is a top view of the claimed design.

The ornamental design which is claimed is shown in solid
lines in the drawings. The evenly dashed broken lines
illustrate portions of the faucet and soap dispenser set and
environment that form no part of the claimed design.
